UNITED STATES PATENT OFFICE

JAMES R. HUGHES, OF SOUTH BEND, INDIANA, ASSIGNOR TO THE STUDEBAKER CORPORATION, OF SOUTH BEND, INDIANA, A CORPORATION OF NEW JERSEY

DESIGN FOR A FENDER LAMP

Application filed May 1, 1930. Serial No. 35,453. Term of patent 14 years.

To all whom it may concern:

Be it known that I, JAMES R. HUGHES, a citizen of the United States of America, and resident of South Bend, in the city of St. Joseph and State of Indiana, have invented a new, original, and ornamental design for a Fender Lamp, of which the following is a specification, reference being made to the accompanying drawing, forming a part thereof.

In the drawing, Figure 1 is a perspective view looking from the rear of the fender lamp showing my new design, and Figure 2 is a perspective view of the fender lamp looking from the front.

I claim:

The ornamental design for a fender lamp substantially as shown.

Signed by me at South Bend, Indiana, this 28 day of April, 1930.

JAMES R. HUGHES.
